UNITED STATES PATENT OFFICE

155,350

DESIGN FOR A KNOB

Harry J. Lebherz, Frederick, Md., assignor to The Everedy Company, Frederick, Md., a corporation of Maryland

Application February 27, 1948, Serial No. 144,774

Term of patent 14 years

(Cl. D44—29)

To all whom it may concern:

Be it known that I, Harry J. Lebherz, a citizen of the United States, residing at Frederick, in the county of Frederick and State of Maryland, have invented a new, original, and ornamental Design for a Knob, of which the following is a specification, reference being had to the accompanying drawing, forming part thereof.

Fig. 1 is a perspective view of a knob, showing my new design;

Fig. 2 is an end elevational view;

Fig. 3 is a top plan view; and

Fig. 4 is a side elevational view thereof.

The dominant features of the design reside in the parts drawn in full lines as shown.

I claim:

The ornamental design for a knob, as shown and described.

HARRY J. LEBHERZ.
